UNITED STATES PATENT OFFICE.

PETER COOPER HEWITT, OF NEW YORK, N. Y.

VENTILATING APPARATUS AND METHOD.

1,133,027.

Specification of Letters Patent. Patented Mar. 23, 1915.

Application filed September 25, 1907, Serial No. 394,484. Renewed February 12, 1915. Serial No. 7,792.

To all whom it may concern:

Be it known that I, PETER COOPER HEWITT, a citizen of the United States, and a resident of New York city, in the county of New 5 York and State of New York, have invented certain new and useful Improvements in Ventilating Apparatus and Methods, of which the following is a specification.

This invention involves the use of a fan 10 to produce a gentle movement of air, particularly applicable for use in connection with office desks, work tables, or dining tables, particularly the smaller tables commonly used in restaurants.

15 One of the objects of my invention is to utilize the induced draft of a small fan to produce gentle movement of the air over a horizontal or upwardly exposed surface and also a comparatively diffused forced draft 20 in the opposite direction above the induced draft and preferably in a plane approximately parallel therewith.

In an ordinary ventilating fan of the propeller type, the air drawn into the fan comes 25 from all directions, including such part of the space in front of the fan as is not occupied by the jet or forced discharge therefrom. The result is that at a very short distance from the fan, the movement of the air 30 is along lines which are approximately the radii of a sphere, so that the rate of movement of air decreases approximately as the cube of the distance therefrom. As a consequence, an ordinary ventilating fan produces no induced draft capable of effective 35 use, and the forced draft is practically the sole agent of ventilation.

I have discovered that the induced draft of a comparatively small propeller fan of 40 low power may be localized adjacent the surface of a table or desk by arranging the fan on a substantially vertical axis and causing it to discharge upwardly, provided the fan be located at a distance from the table not 45 greater than its own diameter. Such an arrangement will produce a very perceptible draft over quite an extent of surface, but the air supply for the induced draft is still derived from the extensive spaces not cut off by 50 the table or by the upwardly discharged draft. By my invention I still further localize the induced draft, and at the same time usefully apply the forced draft by arranging a plate or deflector adapted to dis- 55 tribute the jet of the forced draft in a plane which may be loosely described as horizon-

tal, by arranging in the line of the axis of the fan a plate which distributes the air in a thin layer in all directions. If this plate is near enough to the table and is so arranged that the outgoing sheet of air has its lower surface approximately parallel with the table, then all regions above the plane of the fan are cut off as a source of supply for the induced draft and all of the air necessary to satisfy the latter must be derived, either by air drawn in over the surface of the table or deflected and whirled back from the outgoing forced draft. By this arrangement a large part of the space from which air may be drawn is cut off, and the speed of movement of the induced draft in the remaining space is proportionally increased. This results in producing at the edges of an ordinary table, at a distance 75 from the fan equal to, say, 1½ to 3 or 4 times the diameter of the fan, a very perceptible inward movement of the air which is particularly effective in cooling the body of a person sitting at the table. The action 80 on the hands and wrists is particularly noticeable and effective, and at the same time the draft at the surface of the table is of such gentle and diffused character as not to disturb papers or other light articles lying 85 upon the table.

By making the disk of sufficient size, say 1½ diameter of the fan, and locating it a suitable distance from the same, say ½ diameter of the fan, I have succeeded in producing an almost completely closed circuit of draft, the forced jet from the fan being deflected by the plate in a slightly downward direction and a large fraction of the outgoing air being drawn back in the form of induced draft. In such case, the diameter of the whirl or vortex ring will be something like 3 or 4 diameters of the fan. While this approximately closed circuit localized draft is useful for some purposes and is 95 within the spirit of my invention, I prefer a wider or more open draft circuit. To this end, I may employ a smaller deflecting plate, so arranged that the lower surface bounding the outgoing layer of air will be substantially horizontal or even somewhat inclined upwardly. With such an arrangement, the outgoing forced draft forming the upper layer and the incoming induced draft nearer the surface of the table, will 105 be more independent of each other and the amount of continuously circulated air taken 110

by the induced draft from the outgoing forced draft will be less, so that where the table is of a size equal to about 3 or 4 diameters of the fan, there will be a very considerable localized induced draft of air coming up over the edges of the table at the point where the wrist is likely to be, particularly where the table is used for dining or similar purposes.

10 I have found that in the case of propeller fans of ordinary commercial design, the induced and forced drafts will have the above explained desirable qualities when the upper edges of the fan blades are located above the 15 table a distance not greater than 1 diameter of the fan and the deflecting plate is located above the fan a distance not greater than $\frac{1}{2}$ the diameter of the fan. For most purposes, I prefer to have the fan about $\frac{3}{4}$ of its diameter above the table and the disk about $\frac{1}{4}$ of a diameter above the fan. The diameter of the disk is preferably about $1\frac{1}{2}$ diameters of the fan.

15 It is obvious that the above invention is 20 to consist essentially of a power fan and a deflector held in the above described relations to each other and to the table or similar surface.

25 My invention further contemplates the 30 concrete useful embodiment of the invention adapted for portable use and application to or removal from a desired location upon any suitable table or desk.

35 Referring to the drawings: Figure 1 is a diagram illustrating the essentials of my invention. Fig. 2 is an elevation of a useful concrete form of the invention.

40 Referring to Fig. 1, it will be seen that the fan 1, mounted on the vertical axis 2, is 45 located a distance above the horizontal table 3 equal to its own diameter. The deflecting disk 4 is located $\frac{1}{2}$ diameter above the fan concentrically therewith and has a diameter $1\frac{1}{2}$ times the diameter of the fan. If the 50 disk 4 is made $1\frac{1}{2}$ times the diameter of the fan, as indicated in dotted lines at 5, and the table is moved to the position 3', the relations will approximate those at which the closed circuit or vortex draft above described becomes apparent. It will be obvious 55 that the disk may be a cone or modified cone, and that it may be of various sizes and of different distances from the fan, but all such shapes, diameters, and distance should 60 be regulated with a view to the function to be served and, as a general rule, the outgoing layer of air should be arranged to have its lower surface not more than thirty degrees above the horizontal.

65 In Fig. 2 I have shown a concrete embodiment of my invention, wherein the distance of the fan 11 from the base 13 is considerably less than one diameter of the fan and the distance of the deflecting plate 14 from 70 said fan is less than $\frac{1}{2}$ diameter and more

than $\frac{1}{2}$ diameter. The deflecting plate is of a diameter equal to about $1\frac{1}{2}$ diameters of the fan and is made in the form of a tray, which may be utilized to support ornaments, flower receptacles, or condiment dishes of 75 various kinds. The motor case of the fan is supported by spring arms 6, 6, etc., secured adjustably or otherwise to the uprights 7, 7, etc., which support the upper tray. These uprights may be connected together at the bottom, or may be left as legs adapted to rest upon the table or desk and to support the fan at the desired distance therefrom. As shown in the drawing, the legs are secured to a second tray 23, which 80 is similar to the upper tray. The motor case is preferably steadied in position by means of a support 8, which is preferably of rubber or similarly elastic material intended to 85 deaden vibration.

90 The relative distances of the fan from the table and from the deflector may be adjusted by means of spacing sleeves of suitable length, which may be mounted or removed as at 8', 8', Fig. 2.

95 The sides of the structure between the base 13 and the upper deflecting tray 14 are preferably left open and substantially unobstructed so that both the induced and forced movements of the air may develop naturally and without interference, save only by the deflecting plate above and the table below. This need not prevent the use of an open work cage of wire or similar material, such as is commonly used to prevent 100 accidental contact with the fan while in motion, nor of a vertical shield to close in and prevent all draft around a portion of the periphery to thereby still further limit directions from which the induced 105 draft may be supplied. This condition is approximated where the fan is located on the end of a restaurant table adjacent a wall of the room. In such case the essentials of 110 my method may still be practiced or the closed circuit vortex operation may be approximated with any desired degree of perfection. The difference is that the development of the draft is one sided, instead of 115 symmetrical.

120 Where the deflector is in the form of a flat plate, it will impair the efficiency of the fan if located less than $\frac{1}{2}$ fan diameter away from the fan. Where a flat cone is used, the vertical distance between it and the upper edge of the fan blade at the widest portion of the blade should be greater than $\frac{1}{2}$ of the diameter of the fan, otherwise the fan tends to operate as a very inefficient air 125 compressor, the power apparently being expended in compressing the air between it and the deflector. In such case the compressed air passing beyond the periphery of the fan tends to expand in all directions and a large proportion of it returns di- 130

rectly to the back side of the fan to satisfy the induced draft, the circuit being too small for useful ventilating purposes.

For purpose of low velocity ventilation for comparatively small spaces, such as is contemplated by my present invention, I prefer to use a motor fan of standard type having blades, say, six to ten inches in diameter and a motor of, say, $\frac{1}{8}$ to $\frac{1}{16}$ of a horse-power, since the device when properly proportioned for such motor fans is of very convenient size for table or desk use. The outward forced draft may be of about the proper direction to take effect directly on the neck and face of the user and may be so gentle as to permit of continued direct application without producing a chill or other objectionable effects. By adjustment after the manner hereinbefore described the outgoing forced draft may be made to follow a more or less closed circuit of movement and may be thus more or less completely diverted from direct impingement on the body, if desired.

I claim:

1. The combination with a motor fan, base plate, and tray of means for holding said base plate and tray in approximately parallel relation at a distance apart not less than the diameter of said fan, and means for supporting said motor fan between said tray and said plate with its axis substantially concentric with said tray and with the propeller of the fan arranged with its forced draft side nearer to the tray than to the base plate.

2. The combination with a motor fan and two trays of means for holding said trays

in approximately parallel relation at a distance apart not less than the diameter of said fan, and means for supporting said motor fan between said trays with its axis substantially concentric with said trays and with its propeller distant from the deflecting tray on the forced draft side about one-half as far as its distance from the tray on the induced draft side.

3. A combined table utensil and ventilating apparatus, comprising a tray, supports secured thereto, adapted to hold the tray at a distance from the table approximately equal to the diameter of said tray, in combination with a motor fan of diameter slightly less than said tray, arranged beneath the same and parallel therewith, spring supports extending from the fan motor case to said tray supports, and elastic supporting means for steadyng the lower end of said motor case.

4. A portable device for ventilating tables and the like, comprising a base plate, a deflecting plate disposed above the base plate, an upwardly directed motor fan of slightly less diameter than the deflecting plate disposed between said base plate and deflecting plate, and supports disposed around the fan and connecting the base plate and deflecting plate.

Signed at New York city in the county of New York and State of New York this sixth day of September A. D. 1907.

PETER COOPER HEWITT.
